FURNITURE CHEST

Borge H. Jensen, P.O. Box 699, Brookings, Oreg. 97415

Filed Jan. 8, 1968, Ser. No. 10,093

Term of patent 3½ years

Int. Cl. D6—01

U.S. Cl. D33—19

FIG. 1 is a perspective view of a furniture chest embodying my new design;

FIG. 2 is a front elevational view thereof drawn to a reduced scale;

FIG. 3 is a sectional view taken along the line 3—3 of FIG. 2; and

FIG. 4 is an end elevational view taken from the left in FIG. 2 and drawn to the scale of FIG. 2.

The back of the chest is the same in appearance as the front thereof.

The dominant features of my new design reside in those portions shown in full lines in the drawing.

I claim:

The ornamental design for a furniture chest, substantially as shown and described.
